UNITED STATES PATENT OFFICE.

JOHN HOWARD POSTON, OF EUFAULA, ALABAMA.

COTTON-CLEANER.

SPECIFICATION forming part of Letters Patent No. 339,464, dated April 6, 1886.

Application filed June 17, 1885. Renewed Mar. 12, 1886. Serial No. 193,807. (No model.)

To all whom it may concern:

Be it known that I, JOHN HOWARD POSTON, a citizen of the United States, residing at Eu-
5 faula, in the county of Barbour and State of Alabama, have invented certain new and use-
ful Improvements in Cotton-Cleaners, of which the following is a description.

This invention relates to cotton-gin mills; and its object is to withdraw the dust and dirt
10 from the condenser and from the gin-room, whereby the lint is straightened out into bet-
ter fiber and the gin-room is rendered healthier and more comfortable.

To this end my invention consists in the
15 construction and combination of parts forming the cotton-cleaner, hereinafter described
and claimed, reference being had to the accompanying drawing, which is a sectional
elevation of a portion of a cotton-gin house
20 showing my invention.

A represents a cotton-gin of any usual con-
struction, provided, as usual, with a condenser
in which a cylindrical screen, B, revolves con-
tinually. The ginned cotton passes over the
25 said screen B, in order that the dust and dirt
contained in the cotton may have an oppor-
tunity to fall out. By my invention the fall-
ing of the dust is aided by suction produced
30 by a fan, D, placed below the screen B, and
communicating therewith both at the lower
side and at the ends thereof by a passage, F.
This passage is provided with a gate, G, by
means of which the draft may be regulated.

E is a discharge pipe leading from the fan

35 to any convenient point for discharging the dust and dirt which are withdrawn from the cotton.

I is a pipe leading from the gin-room into the fan below the gate G, whereby the dust in the air may be drawn into the fan and dis-
charged.

J is a gate in the pipe I, to close the same or to regulate the opening thereof.

By means of the gates G and J, the whole draft of the fan may be directed to either the 45 condenser-chamber or to the gin-room, or the draft may be regulated to any degree or be entirely shut off from either passage. More of the dirt in the cotton will be extracted by this forcible draft than would be withdrawn 50 where the mere weight of the dirt is trusted to for its withdrawal.

Any style of fan or exhaust pump or blower may be used at D, instead of the common fan shown.

What I claim as my invention, and desire to 55 secure by Letters Patent, is—

The combination, in a cotton-cleaner, of a 60 revolving screen, an air-exhausting device, a passage leading therefrom to the said screen, 6c a gate in the passage, another passage leading from the gin-room to the exhausting device, and a gate therefor, substantially as shown and described.

JOHN HOWARD POSTON.
